(57) **CLAIM**

The ornamental design for a winch apparatus for a truck cargo bay, as shown and described.

DESCRIPTION

FIG. 1 is a front perspective view of a winch apparatus for a truck cargo bay, showing my new design;
FIG. 2 is a right-side elevation view thereof;
FIG. 3 is a left side elevation view thereof;
FIG. 4 is a front elevation view thereof;
FIG. 5 is a rear elevation view thereof;
FIG. 6 is a top plan view thereof;
FIG. 7 is a bottom plan view thereof;
FIG. 8 is a front elevation view of the winch apparatus for a truck cargo bay shown in condition of use; and,
FIG. 9 is a front elevation view thereof; shown in an alternate condition of use.

The broken lines of the truck in FIG. 8 and FIG. 9 depict environment that form no part of the claimed design.
